UNITED STATES PATENT OFFICE.

SAMUEL STEINFELD, OF BROOKLYN, NEW YORK.

GAME.

Application filed June 22, 1926. Serial No. 117,783.

The present invention relates to improvements in amusement devices, and more particularly to that type of apparatus by which a test of the skill of one or more persons, in accomplishing some sought result, may be obtained. The invention pertains to a game which is adapted to simulate some of the features of the pool game as played on a billiard table.

10 The main object of the invention is to provide a game of the type mentioned which is simple in construction, durable in use and which furnishes a cheerful diversion to the user.

15 Another object of the invention is to provide a game of the character specified, the game board of which is so constructed that it forms a closed container for the game pieces, so that the latter cannot be mislaid or 20 lost.

25 A further object of the invention is to so construct the game that, while it is adapted to simulate some of the features of a pool game, it is of such size that it can be carried in the pocket of the user.

With these and other objects in view, which will more fully appear as the nature of the invention is better understood, the same consists in the combination, arrangement and construction of parts hereafter described, pointed out in the appended 30 claims and illustrated in the accompanying drawings, it being understood that many changes may be made in the size and proportion of the several parts and details of 35 construction within the scope of the appended claims, without departing from the spirit or sacrificing any of the advantages of the invention.

40 One of the many possible embodiments of the invention is illustrated in the accompanying drawing, in which:—

Figure 1 is a plan view of a game constructed in accordance with the present invention; and Fig. 2 is a section taken on line 2—2 of Fig. 1.

45 In the drawings, the numeral 10 indicates a casing of rectangular oblong configuration, having a top 11 of transparent material, such as glass. This top may be attached to the casing in any suitable manner, either permanently or detachably. Within the casing is disposed a board 12, which extends in parallel relation to the 50 top 11 and bottom 13 of the said casing and is suitably spaced from the said two ele-

ments. In the case illustrated, the sides 14 of the casing are provided with longitudinal grooves 15, into which the edges of the board are fitted, the said board extending not only from side to side but also from end 16 to end 16 of the casing and being constructed to simulate the top of a pool table. For this purpose three corners of the said board are cut away as shown at 17, to simulate 60 corner pockets of a pool table. There are also provided semi-circular cut-out portions 18 in both longitudinal edges of the said board at the transverse center line thereof, simulating the middle pockets of a pool 65 table.

Adjacent one of the ends 16 of the casing is provided in the board a plurality of sockets 19, in the present case six, arranged in triangular form and adapted to receive 70 the game pieces 20, which are in the form of small balls. These balls are disposed between the board 12 and the top 11 of the device. The diameter of each individual socket 19 is substantially smaller than the 75 diameter of an individual ball. Into the corner pocket 17, opposite the sockets 19, is fitted a chute 21, which slants from the pocket toward the bottom 13 of the casing, the said chute being provided with a stop 80 22, extending above the board 12, as clearly shown in Fig. 2 of the drawings.

In playing the game, the device is held in horizontal position in the hand or both 85 hands of the user, the balls being initially 90 kept against that end wall of the casing to which the chute 21 leads. The aim is to cause the balls to move toward and into the sockets 19. For this purpose, the user slightly tilts the casing forwards, tapping 95 the table with one of the fingers and guiding one ball after the other by slightly tilting the table forwards and backwards from side to side until a ball reaches one of the 100 sockets, repeating the operation until all of the balls occupy the sockets. Whenever a ball leaves the table through one of the cut-out portions, representing the pockets of a 105 pool table, the game is lost. Of course any other rules may be made for conducting the game. The stop 22 serves to prevent the balls from going into the pocket, from which the chute leads when the casing is being rocked in order to bring a ball in alignment with a pocket preparatory to guiding the 110 ball into such pocket. It is also for this reason that the corner of the board opposite

to the chute is left intact, as shown in Fig. 2 of the drawings. In starting the game, the balls below the board are brought onto the board. In order to accomplish this, the 5 device is tilted so that the balls are adapted to enter the chute. Further tilting of the table will then cause the balls to issue from the chute onto the board, on which they are arranged, by manipulating the casing, in a 10 line along one of the ends of the casing, as shown in Fig. 1 of the drawings.

What I claim is:—

1. A game device of the character described comprising a rectangular oblong casing provided with a transparent top, a board within said casing arranged in parallel relation to said top, extending throughout the entire area of the top and being spaced from the latter and from the bottom of said casing, said board being provided in three of its corners with cut-out portions and also in each of its longitudinal edges with a cut-out portion, said last-named cut-out portions being disposed in the transverse center line 15 of said board, said board being furthermore provided in its upper face with sockets adjacent one of the ends of said casing, a chute leading from the bottom of said casing to one of the cut-out portions in said 20 board adapted to guide the game pieces on the bottom of the casing to the upper face of said board, and a plurality of balls within said casing corresponding in number to the number of the sockets in said board, each 25

of said cut-out portions being of a size 35 larger than the diameter of an individual ball.

2. A game device of the character described comprising a rectangular oblong casing provided with a transparent top, a board in said casing arranged in parallel relation to said top, extending throughout the entire area of the top and being spaced from the latter and from the bottom of said casing, said board being provided in three 40 of its corners with cut-out portions and also in each of its longitudinal edges with a cut-out portion, said last-mentioned cut-out portions being disposed in the transverse center line of said board, said board being furthermore provided in its upper face with sockets adjacent one of the ends of said casing, a chute leading from the bottom of said casing to a corner cut-out portion in said board opposite said sockets, said chute being adapted to guide game pieces on the bottom of said casing to the upper face of said board, a stop on said chute extending above said board, and a plurality of balls within said casing corresponding in number to the number of sockets in said board, each of said cut-out portions being of a size larger than the diameter of an individual ball. 45

Signed at New York, in the county of New York, and State of New York, this 12th day of June, A. D. 1926. 50

SAMUEL STEINFELD. 55
